FLY SWATTER

Henley R. White, Durham, N. C.

Application February 13, 1941, Serial No. 378,829

2 Claims. (Cl. 43—137)

The present invention relates to improvements in fly swatters and more particularly to handles for the same.

An important object of the invention is to provide a fly swatter in which the construction of the handle is such that the body member of the swatter is readily replaced when worn or damaged.

Another object of the invention resides in the provision of a fly swatter embodying novel means for removably retaining the handle in position in the body member.

The invention also consists in certain other features of construction and in the combination and arrangement of the several parts, to be hereinafter fully described, illustrated in the accompanying drawing and specifically pointed out in the appended claims.

In describing my invention in detail, reference will be had to the accompanying drawing wherein like characters denote like or corresponding parts throughout the several views, and in which:

Figure 1 is an elevational view of a fly swatter embodying the features of the present invention.

Figure 2 is an exploded view illustrating the manner of positioning the handle in the body member.

Figure 3 is a sectional view taken substantially on line 3—3 of Figure 1.

Referring to the drawing for a more detailed description thereof, the improved fly swatter is generally designated by the reference numeral 5 and includes a substantially rectangular-shaped body member 6 formed of wire gauze or the like, the edges of which are bound by means of a tape 7 stitched or otherwise secured to the body member.

The handle of the fly swatter is generally designated by the reference numeral 8 and consists of a single strand of wire folded intermediate its ends and bent upon itself as indicated at 9 to form a hand retaining loop 10. The body member 6 has its two corners at one end folded over and held by stitching or suitable similar means indicated by the reference numeral 11 to form pockets for receiving the ends 12 and 13 of the handle 8, which ends diverge outwardly at an angle to the handle. The normal position of the ends of the wire from the point of twisting 9 is shown in Figure 2 and it will be observed that the formation of the handle is such that the wires cross at the points 14 and 15. However, when in the position shown in Figure 1 the ends extend substantially parallel from the twisted portion 9 and are held in position by means of a loop 16, corrugations 17 being formed in the handle for preventing movement of the loop 16 toward the end of the handle.

When initially positioning the handle, the loop 16 will be held in the manner shown in Figure 2 of the drawing and the ends 12 and 13 urged

therethrough into the pockets at the folded ends until the ends of the handle assume the position shown in Figure 1. After the handle has been moved into fixed position with the body member 6, the ends of the handle will be substantially parallel and the loop 16 will be in engagement with the corrugations 17 serving to maintain the ends 12 and 13 within the end pockets of the body member.

When it becomes necessary to replace the body member 6, said member will be firmly held and pressure exerted outwardly on the handle 8 to effect disengagement of the ends 12 and 13 from the pockets. While disengaging the ends 12 and 13, the loop 16 will at the same time be urged to the position shown in Figure 2. Thus it will be seen that the handle 8 is readily and easily positioned and removed from the body member when initially assembling the swatter or when it is necessary to replace a worn body member.

Also it will be understood, of course, by those skilled in the art that variations in the hereinabove described device involving the substitution of substantial equivalents for the devices described are intended to be comprehended within the spirit of the present invention and that the invention is capable of extended application and is not confined to the exact showing of the drawing nor to the precise construction described and, therefore, such changes and modifications may be made therein as do not affect the spirit of the invention nor exceed the scope thereof as expressed in the appended claims.

What is claimed is:

1. A fly swatter of the character described, comprising a substantially rectangular shaped body member formed of wire gauze material having folded corners constituting obliquely arranged pockets, a handle for said body formed of wire with two outwardly diverging portions terminating in two converging portions crossed at their free ends, and a wire loop slidable on the inwardly converging portions for forcing the said portions outwardly within the obliquely arranged pockets in the body member.

2. A fly swatter of the character described, comprising a substantially rectangular shaped body member formed of wire gauze material having folded corners constituting obliquely arranged pockets, a handle for said body, said handle formed of a single piece of wire twisted intermediate its ends, the ends of the wire diverging outwardly from the twisted portion and terminating in converging portions crossed at their free ends, and a wire loop slidable on the converging portions in beyond their crossed ends for forcing said portions outwardly within the obliquely arranged pockets in the body member and maintain the same therein.
